United States Patent Office

Des. 216,060

Patented Nov. 18, 1969

216,060

ASHTRAY

Jean-Luc Vincent, 6 Avenue de Thonex,
Geneva, Switzerland

Filed Mar. 14, 1969, Ser. No. 16,255

Term of patent 14 years

Int. Cl. D27—03

U.S. Cl. D85—2

FIG. 1

FIG. 2

FIG. 3

FIG. 5

FIG. 4

FIGURE 1 is a perspective view showing the ashtray of the present invention;

FIGURE 2 is a side elevational view of the ashtray;

FIGURE 3 is an end elevational view of the ashtray;

FIGURE 4 is a top plan view of the ashtray; and

FIGURE 5 is a bottom plan view of the ashtray.

Portions of the drawing figures have been stippled to indicate contrast in appearance.

I claim:

The ornamental design for an ashtray, as shown and described.
